IMPROVEMENT IN APPARATUS FOR FINISHING AND BOXING PAPER COLLARS.

JOHN J. CURRIER AND SAMUEL WELLS, JR., OF BOSTON, MASSACHUSETTS,
ASSIGNORS TO THEMSELVES AND JAMES H. PLAISTED.

Letters Patent No. 60,484, dated December 18, 1866.

The Schedule referred to in these Letters Patent and making part of the same.

TO ALL WHOM IT MAY CONCERN:

Be it known that we, JOHN J. CURRIER and SAMUEL WELLS, Jr., of Boston, in the county of Suffolk, and Commonwealth of Massachusetts, have invented a new and useful Machine for Finishing and Boxing Shirt Collars made of paper, or paper combined with other material; and we do hereby declare that the following is a full and exact description thereof, reference being had to the annexed drawings, and to the letters of reference marked thereon, the same parts being marked by the same letters in all the figures, of which—

Figure 1 is a perspective view.

Figure 2 is a transverse section of the rollers, cylinder, and piston.

Figure 3 is a vertical section of the rollers, separated.

Figure 4 is a plane view of a section of the boxing-wheel.

Figure 5 is a plane view of the wheels for turning the rollers and piston.

Figure 6 is a vertical section of the cylinder and piston, and a collar box, which is represented by dotted lines below.

Figure 7 is a plane view of the under side of the cam-wheel, 10; and

Figure 8 is a vertical section of the pulley, 9, showing the mode of keying it to prevent vertical motion.

Our invention consists in an apparatus for pressing and winding up shirt collars made of paper or paper combined with other material, so contrived as to finish the fold of the collar in the line previously defined, and impart to it the curved form necessary to enable it to fit round the neck; and in combination therewith a device for putting the finished collar in a box, and supplying an empty box when the first is filled with the required number.

It is not a new process to pass such collars between rollers which press on the fold and finish it, but in so treating collars, bent on a curved line, a difficulty has been experienced, owing to the fullness in the outside part, in preventing the rollers from running off from the defined line and folding the collar in the wrong place, and consequently spoiling it. Several contrivances have been resorted to for overcoming this difficulty, but it is unnecessary to enumerate them.

Our invention is designed to finish collars folded on a curved line by winding them up in a small compass as they escape from the pressure roller. This process takes up the fullness of the outside part and enables the roller to press on the desired line of fold with the necessary pressure.

Having wound the collar up, it is in a suitable form to place in a box; we therefore so dispose of it by the machine hereinafter described, and the natural elasticity of the material causes the collar to spring outward toward the sides of the box.

The machine invented by us is represented in a perspective view in fig. 1.

It consists of a frame, A A, a driving-wheel, 1, which carries the wheel, 2, on the roller, D, and through the wheels, 3, on top of the spindle of said roller, D, and wheels 4 and 5, the rollers B and C. The roller B is cylindrical; the rollers C and D are conical for a portion of their length; it is not, however, necessary to our invention to make them conical—they may be cylindrical; and we do not claim as our invention the use of conical rollers, or the arrangement of the rollers separate from the whole machine. The guide, O, serves to direct the collar between the rollers, B and D. The passage-way, E, represented in fig. 2 and fig. 6, conducts the collar to the cylinder, E, in which revolves the piston, F; the surface of this piston is covered with rubber, so elastic that it will carry the collar round by friction, and at the same time leave space between its surface and the interior surface of the cylinder for the collar when wound up. This object may be attained by attaching the rubber in the shape of projecting points, like those of wheel 8, or by inserting pieces of sheet rubber, or other elastic material, at short intervals. The piston, F, has a cap, F', which should fit the cylinder as closely as possible, so as to push the wound-up collar down out of the cylinder. The piston, F, is revolved by its shaft, G, which receives a rotary motion from the wheel, 8, which is loosely keyed on the shaft so as to allow it to move vertically without checking its revolution. The wheel, 8, is prevented from moving vertically by a key fastened in the frame, as represented in the vertical section of wheel 9, in fig. 8. The wheel 8 receives motion from the carrying-wheel, 7, and that from the pinion, 6, on the spindle of the roller, B. The shaft, G, receives a vertical

reciprocating motion at fixed periods of time, so that after the rollers and piston have revolved sufficiently to wind up a collar in the cylinder, the shaft shall depress the piston and deposit the collar in the box, as represented in fig. 6. This reciprocating motion is communicated by the forked lever J, the fulcrum of which is at K, and which has pins on each of its forks that catch into the slots in the ring, H. The shaft, G, turns freely in this ring, but having on each side of the ring pins, I, I, is moved vertically by the motion of the ring. The shaft, G, carries the wheel, 9, which has a projection catching in the slot of the shaft like that of wheel 8, as represented in fig. 8. Wheel 9 carries the cam-wheel 10, which has on its under side a depression gradually increasing from a to b , as represented in fig. 7. When in its revolution the point, b , comes over the end of the rod, M, the end of the rod flies up into the said depression by force of the spring, N, which pulls up the lever, J, and the rod, L, attached to it, and thereby lifts the end of the bell-crank, Q, on which rests the lower end of the rod, M. The motion thus given to the lever, J, by the spring, N, depresses the shaft, G. As the cam-wheel, 10, moves on it pushes down the rod, M, by force of the inclined plane between a and b . Said rod, M, in descending moves the bell-crank, Q, which has an arm, R, catching into the teeth of the ratchet-wheel, U, and pressed against the said wheel by the spring, R'. The arm, R, has a pin, T, and when the wheel, U, is so turned that the projection, V, strikes the arm, R, it throws the said arm out so that the pin, T, strikes the lever, S, and moves it. Z is a pawl to keep the wheel, U, from turning the wrong way. W W W are wires with bent ends to hold a box in which to deposit the finished collar. P is a section of the boxing-wheel. On the rim of it, at regular intervals, equal to the distance between the centres of the boxes, are placed ratchet-wheels, with wires, &c., one of which has just been described. Such ratchet-wheel will move one tooth each time a collar is placed in the box, which rests on the wires, and if it has ten teeth, when the tenth collar is boxed, the projection, V, will throw the arm, R, out, so that as it is moved by the bell-crank, Q, the pin, T, will strike the lever, S, which turning on a fulcrum at S'', moves the pawl, S', and the ratchet-wheel, X, one tooth. The ratchet-wheel, X, is at the centre of the boxing-wheel and carries said wheel round. A movement of X one tooth, therefore, carries away the box which has been filled and supplies its place with an empty box. The ratchet-wheel, X, should have as many teeth as there are boxes on the wheel, which may be as large as is convenient. Y is a pawl to keep the wheel, X, from turning the wrong way.

We do not limit ourselves to these particular devices for moving the wheels U and X, as they may be varied according to the mode of applying power to the machine. The principle of this part of our invention consists in an automatic apparatus for removing a box when filled with a certain number of collars and supplying its place with an empty box. As it is not necessary to move the box each time a collar is placed in it, instead of having a ratchet-wheel for each box, one such wheel will answer for all, if it is so arranged that when it has completed one revolution it will move the lever, S, and bring up an empty box. It is obvious to any skillful workman that this can be done by simply placing the wheel, U, beyond the end of the lever, S, and fastening it there permanently, and also placing the arm, R, outside of S, with the pin, T, on the other side of R. With this arrangement, at each revolution of the wheel, U, the projection, V, would throw the arm, R, so that the pin, T, would move the lever, S. S³ is a spring to carry back the lever S after it has been moved by the pin T.

The operation of our machine is as follows: We take a shirt collar made of paper, or paper combined with other material, on which the line of fold has been defined and which has been partially folded, and place one end thereof between the rollers, B and C, the inside of the collar against the roller B. The collar is pressed by said rollers, and carried by them between the guide, O, and the roller, B, till it comes between the rollers D and B, where the fold is firmly pressed; it then passes along the passage-way, E', till it reaches the cylinder, E, where, coming in contact with the elastic surface of the piston, F, it is by the friction of this surface against the interior surface of said cylinder carried round said cylinder and wound up. The cam-wheel 10 then brings the point, b , over the end of the rod, M, which enables the helical spring, N, to contract and lift the end of the lever, J, depressing the forked end of said lever, and by it the ring, H, and the shaft, G. The cap, F', of the piston, F, presses the top of the wound-up collar and forces it down into the box below. When the cap, F', reaches the bottom of said cylinder, E, the collar is released therefrom, and the natural elasticity of the material of which it is composed causes it to spring outward toward the circumference of the box, and so leaves space in the centre for another collar to be deposited within it. The contraction of the spring, N, at the same time that it moves the lever, J, lifts the rod, L, and by means of said rod the end of the bell-crank, Q; this motion moves back the arm, R, over one tooth of the ratchet-wheel, U. As the wheel 10 continues to revolve, the inclined plane of the depression, a b , presses down the upper end of the rod, M, the lower end of said rod presses the bell-crank, Q, which carries forward the arm, R, and moves the wheel, U, one tooth; the bell-crank, Q, by this movement also draws down the rod, L, and by it the end of the lever, J, expanding at the same time the spring, N. The lever, J, raises the shaft, G, and another collar may be inserted. After the required number of collars to fill a box have passed through the machine, the wheel, U, will have made a revolution, and the projection, V, will push out the arm, R, which in its motion forward will catch the lever, S, by the pin, T, and turn the boxing-wheel, bringing up an empty box.

The different parts of our machine may be made nearly of the size represented in the drawings, excepting, of course, the section of the boxing-wheel marked P.

What we claim as our invention, and desire to secure by Letters Patent, is—

1. A machine for finishing and boxing shirt collars made of paper or other material, consisting of the rollers B, C, and D, cylinder E, piston F, and wheel P, arranged and combined substantially as described.
2. The combination and arrangement of the cylinder E, piston F, and rollers B, C, and D, substantially as and for the purpose specified.
3. The wheel P, and the devices for moving the same, consisting of cam 10, rod M, bell-crank Q, arm R, ratchet-wheels U and X, arm V, lever S, rod L, and spring N, substantially as described.

4. The combination and arrangement of the cylinder E, piston F, and wheel P, said wheel having devices attached for giving it an intermittent motion, substantially as described.

5. The combination and arrangement of the cylinder E, piston F, shaft G, lever J, ring H, rods L and M, spring N, and cam 10, substantially as and for the purpose specified:
